Patented May 17, 1966

204,770

TOY CRANE

Robert D. Pfister, Westport, Conn., assignor to De Luxe
Reading Corporation, Elizabeth, N.J., a corporation of
New Jersey

Filed Mar. 16, 1965, Ser. No. 84,295

Term of patent 3½ years

(Cl. D34—15)

FIG. 1

FIG. 2

FIG. 3

FIG. 4

FIG. 5

FIGURE 1 is a top plan view of a toy crane, showing my new design;

FIGURE 2 is a side elevational view thereof;

FIGURE 3 is a side elevational view of the opposite side shown in FIGURE 2;

FIGURE 4 is a front elevational view thereof;

FIGURE 5 is a rear view thereof.

I claim:

The ornamental design for a toy crane, substantially as shown.
